United States Patent Office

Des. 222,358
Patented Oct. 19, 1971

222,358

ANTENNA

Franklin Roosevelt Di Meo, Woodbury, N.J., and Neil Worrall Burwell, deceased, late of Moorestown, N.J., by Shirley D. Burwell, legal representative, Moorestown, N.J., assignors to RCA Corporation

Filed Dec. 29, 1969, Ser. No. 20,656

Term of patent 14 years

Int. Cl. D14—99

U.S. Cl. D26—14

FIG. 1 is a perspective view of an antenna showing our new design, the undisclosed underneath portion being substantially the same as the top portion shown; and

FIG. 2 is another perspective view of the antenna with one of the members of the antenna in an alternate position.

We claim:

The ornamental design for an antenna, as shown and described.
